J. J. BONER.

LOCK.

APPLICATION FILED APR. 2, 1921.

1,438,089.

Patented Dec. 5, 1922.

UNITED STATES PATENT OFFICE.

JOHN J. BONER, OF BLUE ISLAND, ILLINOIS.

LOCK.

Application filed April 2, 1921. Serial No. 457,954.

To all whom it may concern:

Be it known that I, JOHN J. BONER, a citizen of the United States, residing at Blue Island, in the county of Cook and State of Illinois, have invented new and useful Improvements in Locks, of which the following is a specification.

This invention relates to locks and more particularly to a lock designed for use on 10 freight cars to prevent theft of the merchandise therefrom.

An object of the invention is to provide a key operated locking structure which will co-operate with the sliding bolt used on 15 freight or refrigerator cars in such a manner as to prevent the opening of the door even in case the seal is broken and further to provide a lock structure which will permit cars to be locked without sealing but if sealed 20 in the usual manner the bolt must be locked.

Another object of this invention is to provide a lock structure as specified which comprises a movable bolt adapted for insertion through the ordinary bolt of a car door 25 which lock bolt is moved out of locking position by rotation of a disc, the said disc normally being held in locked position by a suitable latch releasable by a key.

Other objects of the invention will appear 30 in the following detailed description and in the accompanying drawings wherein:

Fig. 1 is a fragmentary side elevation of a freight car showing the lock applied and 35 having a part broken away to expose the lock construction in locked position.

Fig. 2 is a detail side elevation of the lock, partly in section, showing it in an unlocked position.

Fig. 3 is a section through the lock taken 40 on the line 3-3 of Fig. 2 showing the key inserted.

Fig. 4 is a detailed view of the key.

Fig. 5 is a detail side elevation illustrating 45 the manner in which the ordinary bolt covers the key hole of the improved lock.

Fig. 6 is a view similar to Fig. 5 showing the parts in another position with a portion broken away.

Referring more particularly to the drawings 50 the improved lock structure is preferably carried by the door frame of a freight or refrigerator car, for which the lock is particularly adapted, however, it is to be understood 55 that the lock may be used in connection with any type of opening closure mem-

ber desired without departing from the spirit of this invention.

The improved lock comprises a guide 1 which is provided with a longitudinally extending bolt receiving slot 2 adapted to slidably receive therein the ordinary locking bolt 3, such as used in connection with the locking pins and seals in freight cars at the present time. The locking bolt 3 is provided with a transversely extending opening 4 which is adapted to receive therethrough the locking bolt 5 of the lock structure when the latter is in locking position as shown in Fig. 1 of the drawing. The bolt 5 extends 65 transversely to the bolt 3 and it is provided with rack teeth 6 formed part way along one edge thereof. The rack teeth 6 are provided for co-operation with the gear teeth 7 formed upon the perimeter of the disc 8 70 of the lock structure. The disc 8 is rotatably supported and has a rectangular axial spindle 9 formed on its outer face as well as being provided with a pair of rectangular openings 10 disposed, preferably, at 90° 75 angle to each other and having their innermost portions connected by an arcuate slot 11. The rectangular openings 10 are provided for receiving the latch bolt 12 which extends transversely to the disc 8 and is urged by a spring 13 into one of the rectangular openings 10 outwardly of the arcuate slot 11 for locking the disc 8 against rotation. A slideable arm 14 carries the latch 80 bolt 12 and is urged downwardly by the spring 90 12. The arm 14 projects downwardly and has its lower end 15 positioned in the path of a cleat 16 on the bolt 3 so that when the bolt 3 is inserted in the guide 2 the cleat 16 95 will engage the arm 14 and move this arm 95 upwardly, forcing the latch bolt 12 into alignment with the arcuate slot 11.

In locking, when the bolt 3 is moved into place the cleat 16 will move the arm 14 thus moving the latch bolt 12 into registration 100 with the arcuate slot 11 and the weight of the bolt 5 will cause it to drop into locking position, since the disc 8 is mounted for free rotation when the latch bolt 12 is in or moving through the arcuate slot 11. After the 105 lock has been locked, if it is desired to seal the car in the usual manner, the seal pin 22 is inserted through the usual staple 23 on the car outwardly of the clasp 24, which is carried by the bolt 3 and the usual form of seal 110 is inserted, however, as will be noted by reference to Fig. 5 of the drawing, the sealing

bolt 22 passes directly over the keyhole 25 of the lock structure preventing the insertion of a key into the lock until the seal is broken thereby providing double insurance against 5 malicious tampering with the contents of a car equipped with the improved lock.

When unlocking the improved lock; the key 17 is inserted through the key plate 18 with the recesses 19 in the key receiving the 10 spindle 9 and with the arm 20 of the key bit extending through the opening 10 in which the latch bolt is engaged. The inserting of the key in place as above stated will move the latch bolt out of the recesses 10 permitting 15 the disc 8 to be rotated and raise the bolt 5 out of the opening 4 and release the bolt 3 for unlocking movement.

It is, of course, to be understood that the invention may be constructed in various 20 other manners and the parts associated in different relations and, therefore, I do not desire to be limited in any manner except as set forth in the claims hereunto appended.

Having thus described my invention what 25 I claim is:

1. In a lock, the combination with a locking bolt, of a second locking bolt extending transversely thereto and adapted for locking engagement with said first named 30 locking bolt, rack teeth formed upon said said second locking bolt, a rotatable disc having gear teeth on its perimeter for co-acting with said rack teeth, and means normally restraining said disc against rotation.
2. In a lock, the combination with a locking bolt, of a second locking bolt extending transversely thereto and adapted for locking engagement with said first named locking bolt, rack teeth formed upon said second 40 locking bolt, a rotatable disc having gear teeth on its perimeter for co-acting with said rack teeth, and means normally restraining said disc against rotation, a cleat upon said first named locking bolt for releasing said 45 restraining means upon movement of the first named locking bolt into locking position.

3. In a lock, the combination of a locking bolt, a second locking bolt adapted to be moved into locking engagement with the first named locking bolt, rack teeth formed upon said second lock bolt, a rotatable disc, gear teeth upon the perimeter of said disc for engagement with said rack teeth to operate said second lock bolt by rotation of 55 said disc, a latch bolt normally restraining said disc from rotation, and a key for releasing said latch bolt and rotating said disc.

4. In a lock, the combination of a locking bolt, a second locking bolt adapted to be moved into locking engagement with the first named locking bolt, rack teeth formed upon said second lock bolt, a rotatable disc, gear teeth upon the perimeter of said disc 65 for engagement with said rack teeth to operate said second lock bolt by rotation of said disc, a latch bolt normally restraining said disc from rotation, a key for releasing said latch bolt and rotating said disc, and 70 means operable by movement of said first named locking bolt into locking position to release said latch bolt to permit rotation of said disc.

5. In a lock, the combination of a locking 75 bolt, a second locking bolt adapted to be moved into locking engagement with the first named locking bolt, rack teeth formed upon said second lock bolt, a rotatable disc, gear teeth upon the perimeter of said disc 80 for engagement with said rack teeth to operate said second lock bolt by rotation of said disc, a latch bolt normally restraining said disc from rotation, a key for releasing said latch bolt and rotating said disc, an arm 85 engaging said latch bolt, a cleat carried by said first named locking bolt and adapted to engage said arm upon movement of the first named locking bolt into locking position for moving the latch bolt out of movement restraining position relative to said disc.

In testimony whereof I affix my signature.

JOHN J. BONER.
